Attorney.

UNITED STATES PATENT OFFICE

WILLIAM E. WILLEY, OF CHAMPAIGN, ILLINOIS

PERMANENT GOLF TEE

Application filed June 11, 1930. Serial No. 460,361.

The invention relates to improvements in golfing equipment and particularly to an improved permanent golf ball tee and mounting.

6 An object of the invention is to provide an improved permanent golf ball tee which may be employed on indoor or outdoor golf courses.

Another object is to provide an improved 10 device of the character referred to with means for detachably securing, selectively, tees of different heights.

Another object is to provide a permanent 15 tee constructed to stand abuse, such as is encountered by inadvertently striking it with a golf club, or the like.

Another object is to provide an improved 20 permanent tee mounting that will not tend to retard or deflect the swing of a golf club, or the flight of a golf ball therefrom.

Another object is to provide a device of 25 the character referred to, with means adapted to be embedded in a floor or in the ground, and means for readily securing it in place.

Another object is to provide an improved 30 tee and permanent mounting, simple in operation and inexpensive to manufacture.

The foregoing and such other objects of 35 the invention as will appear hereinafter as the description proceeds, will be more readily understood from a perusal of the following specification, reference being had to the accompanying drawing, in which:

Fig. 1 is a perspective view of the improved tee mounted in a floor, shown with a 40 golf ball thereon.

Fig. 2 is a central longitudinal vertical 45 sectional view through the device.

Fig. 3 is a vertical sectional view taken 50 on line 3-3 of Fig. 2.

Fig. 4 is an inverted horizontal sectional 55 view.

Fig. 5 is a perspective view of the improved tee and mounting, shown mounted 60 for outdoor use.

The improved permanent tee structure 65 preferably includes a substantially rectangular plate 11 having a longitudinal slot 12 therein formed with an enlarged end 13. Bearings 14 preferably are formed integral

with the plate 11 and extend downwardly therefrom. These bearings are arranged one on each side of slot 12, adjacent its narrow end, and are integral with a downwardly extending connecting wall 15 adjacent one end of the slot 12. A pin 16, journaled in the bearings 14, provides a rotatable mounting for a hub member 17 extending between the bearings 14. One face 18 of the hub member 17 is flat and is provided with a tapped opening 19 to receive the threaded end 21 of a tee or golf ball support 22.

When the tee 22 is positioned for use, it extends substantially vertically upwardly through the slot 12, and a golf ball 23 is positioned upon the concave upper end 24 of said tee. Proper vertical alignment of the tee 22 preferably is attained by manipulation of an adjusting screw 25 which extends through the wall 15 and is locked in position by a lock nut 26.

To mount the device in a building, an opening 27 having a rabbet 28 is cut in the floor 29. The plate 11 is placed upon the rabbet 28, which is of sufficient depth to dispose the top face of the plate flush with the floor. A suitable receptacle 31, preferably formed of sheet metal, is held in place beneath the plate 11 by flanges 32, extending outwardly of each end wall thereof and overlying the rabbet 28. Screws 33, or other suitable means retain the plate 11 and the receptacle 31 in place. If desired, a rubber mat or carpet 34 (Fig. 4) having a cut-out portion 35 conforming in shape to slot 12, may be placed over the floor 35 and the floor plate 11.

To use the device, the tee is positioned substantially vertically, and a golf ball is positioned thereon, as described in the foregoing. Upon striking the golf ball with a club, the tee 22, together with hub 17, rotates about pin 16, the tee entering the receptacle 31 through slot 12. A suitable U-shaped stop 36 is arranged beneath the plate 11 to limit the drop of the tee and provide a support to hold it in an accessible position. The tee may be raised vertically by grasping its end through the enlarged portion 13 of the slot and swinging it about pin 16.

When the improved structure is used on an

outdoor golf course, the plate 11 preferably is mounted upon the upper end of a hollow box-like structure 37, having upwardly inclined walls. The member 37 also is provided with an anchoring flange 38 around its bottom edge which flange, together with the inclined walls, serves to securely anchor the device in the earth at such depth as to dispose the top plane of the plate 11 at ground level.

Any desired number of plates 11, having a tee pivotally mounted therein, may be arranged in multiples upon a single mounting 37, as shown in Fig. 5. In this instance, each plate is provided with a tee 22a of different height. An arrangement of this character is preferable, as different individuals favor tees of different heights. The plates 11 also may be arranged in multiples for indoor use. Where a single unit is provided, the tee 22 may readily be removed and one of the desirable height inserted.

It can readily be understood that the device described in the foregoing specification and illustrated in the accompanying drawing may embody variations in detail structure without departing from the spirit of the invention or the scope of the appended claims.

I claim:

- 30 1. An article of the class described comprising, in combination, a plate having aligned bearings thereon, a wall connecting said bearings, a hub rotatably mounted between said bearings, a golf ball support removably mounted in said hub adapted to extend substantially vertically through a slot in said plate, means for supporting said support in a non-vertical position, and a stop threaded for adjustment in said wall to limit 40 movement of the support in one direction.
- 45 2. A golf tee comprising, in combination, a plate having a slotted opening therein, aligned bearings extending downwardly from said plate one on each side of the slot adjacent one end of said slot, a wall connecting said bearings at the end of said slot, a hub rotatably mounted between said bearings, threaded means in said wall adjustable to limit rotation of the hub in one direction, a 50 golf ball support adjustably mounted in said hub adapted to extend substantially vertically through the slot when said hub is against said threaded means, and a yoke beneath said slot engageable by said support to limit movement 55 of the hub away from said threaded means.

In testimony whereof I affix my signature at Urbana, Illinois.

WILLIAM E. WILLEY.
